Primary Examiner — Ramzi Almatrahi(74) *Attorney, Agent, or Firm* — Venable LLP(57) **CLAIM**

The ornamental design for a digital video camera, as shown and described.

DESCRIPTION

FIG. 1 is a front view of a digital video camera showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a top, front and left side perspective view thereof;

FIG. 8 is a top, rear and left side perspective view thereof; and,

FIG. 9 is a top, front and right side perspective view thereof, shown in condition of use with a handle disclosed in broken lines to illustrate an environment.

The broken lines depict portions of the digital video camera in which the design is embodied that form no part of the claimed design. The broken lines showing a handle in FIG. 9 represent environmental structure and form no part of the claimed design.
